W. D. Jones,

Gas Consumer.

No 20,351.

Patented May 25, 1858.

UNITED STATES PATENT OFFICE.

WILLIAM D. JONES, OF HAGAMAN'S MILLS, NEW YORK.

IMPROVED APPARATUS FOR SEPARATING THE COMBUSTIBLE FROM THE INCOMBUSTIBLE GASES OR PRODUCTS OF COMBUSTION IN FURNACES, &c.

Specification forming part of Letters Patent No. 20,351, dated May 25, 1858.

To all whom it may concern:

Be it known that I, WILLIAM DAVIDSON JONES, of Hagaman's Mills, in the county of Montgomery and State of New York, have invented a new and Improved Apparatus for Separating the Combustible from the Incombustible Volatile Products or Gases of Combustion from a Furnace and Returning them to the Fire-Place to be Consumed as Fuel; and I do hereby declare that the following is a full, clear, and exact description of the same, reference being had to the accompanying drawings, making part of this specification, in which—

Figure 1 is a vertical central section of the apparatus. Fig. 2 is a partial vertical section in the plane indicated by the line $x\ x$ in Fig. 1.

Similar letters of reference indicate corresponding parts in both figures.

This invention consists in the construction and arrangement of the parts of an apparatus for separating to a certain extent the combustible from the incombustible gases of combustion in such form as to make the apparatus applicable to all steam-boilers or other furnaces or to stoves.

To enable others skilled in the art to make and use my invention, I will endeavor to proceed to describe its construction and operation.

A is a box of square or other form, made of sheet-iron or other material, having at its upper part an inlet-opening a to receive the products of combustion, and above this opening a horizontal perforated or reticulated diaphragm b , which divides it into an upper chamber B and a lower chamber C, the said diaphragm having an opening e near the center, from which a pipe f descends to near the bottom of the box A. The said pipe f has no communication with the lower chamber C, but communicates with the inlet-opening c in one side of a fan-blower D in the lower part of the box A, the outlet from which blower leads through one side of the lower part of the box A, and is intended to have connected with it a pipe leading to the ash-pit or under the grate of the furnace or fire-place. The blower D has an inlet-opening d at the opposite side to c to receive atmos-

pheric air from an open-bottomed box E to mix with the combustible gases which enter the said blower at c . On the opposite side of the pipe f to the blower D there is arranged within the box A another blower F, whose outlet is to lead to the chimney or in a convenient manner to the atmosphere, and whose inlet g is covered by a box G, whose bottom communicates with the chamber C. The entrance n to the box E is fitted with a valve h , and that m to the box G with a valve i , and the pipe f is fitted with a valve j . The fans k of the blower D and those l of the blower F are attached to the same shaft H.

The above-described apparatus is complete in itself and can be applied to any stove or furnace by connecting the inlet a with the fire-box or with the direct or return flue thereof, connecting the outlet of the blower D with the ash-pit or chamber under the fire-grate, which should be otherwise closed, and connecting the blower F with the chimney or providing a suitable means of escape therefrom.

The operation of the apparatus is as follows: The necessary connections being effected, fire having been made, and the blowers set in operation by giving rotary motion to the shaft H, the volatile or gaseous products of combustion entering at a fill the chamber C, in which a great portion of the incombustible products (principally carbonic acid) subsides by reason of their greater specific gravity, while the combustible products (carbonic oxide) rise through the diaphragm b , which breaks the current and acts in a measure as a separator, into the chamber B, from whence they are drawn down the pipe f by the blower D, and thereby carried to the fire with a sufficient quantity of air, which is simultaneously drawn into the said blower through the box E to effect ignition and combustion, the incombustible products being at the same time drawn from the chamber C through the box G by the blower F and conveyed to the chimney or into the atmosphere. The operation is regulated by the valves i , j , and h , a greater opening being given to i if the combustion in the fire-box appears to be smothered by the admission of carbonic acid, or to j when there is, as after a fresh charge of

fuel, an excess of carbonic oxide, and the opening of the valve *h* being regulated to supply more or less air, according to the judgment of the person in charge or by a self-acting governor, which regulates its opening by the pressure in the chamber below the fire.

I do not claim the returning of the combustible portion of the volatile or gaseous products of combustion to the fire, nor do I claim, broadly, the separation of the combustible from the incombustible products by the difference in their specific gravity; but

What I claim as my invention, and desire to secure by Letters Patent, is—

The box *A*, with its inlet *a*, separating-diaphragm *b*, chambers *B* and *C*, pipe or passage *f*, and two fan-blowers *D* and *F*, arranged in the manner substantially as described, and operating as set forth.

WILLIAM D. JONES.
